UNITED STATES PATENT OFFICE.

EDWARD NAUER, OF SAN FRANCISCO, CALIFORNIA.

HEATER.

Application filed December 12, 1927. Serial No. 239,469.

My invention relates to improvements in heaters whereby heat from a gas burner or the like may be efficiently radiated to warm a room.

5 The present invention constitutes an improvement upon the device disclosed in my Patent No. 1,655,658, January 10, 1928, and consists of improved features of construction and arrangement whereby a larger heat 10 radiating area and an increased efficiency is obtained.

The primary object is to provide an improved heater construction.

Another object is to provide an improved 15 device which is operable as an independent heating unit which may be connected to any convenient fuel supply and which may be readily transported and connected for use in desired locations.

20 A further object is to provide an improved heater which will give increased heating efficiency from the fuel consumed.

A still further object is to provide an improved device which can be economically 25 manufactured and which is attractive in appearance.

I accomplish these and other objects by means of the improved device disclosed in the drawings forming a part of the present 30 application wherein like characters of reference are used to designate similar parts throughout the drawing and specification, and in which—

The figure is a vertical mid-sectional view 35 of my improved heater.

Referring to the drawing the numeral 1 is used to designate a base provided with a reduced tapered upper body portion 2 and having a plurality of openings 3 formed in 40 the top thereof. The base is preferably made square in form and the upper body portion 2 is made frusto-pyramidal, with the side walls hipped as at 4 with the upper wall portions converging at a greater angle 45 from the vertical than the lower wall portions. The base 1 is preferably mounted upon legs 6 mounted at the corners thereof, and a burner 7 is mounted across the under side of the base and centrally disposed under the body portion 2 thereof by means of 50 supporting straps 8 and 9. The burner 7 may be of any suitable form and is arranged to receive fuel through a supply connection 10 connected in any convenient manner, not 55 illustrated, to a source of fuel supply. A

shield plate 11 is mounted between the four legs 6 slightly below the burner 7.

A heat diffusing member 12 is mounted upon the top of the body portion 2 of the base, said member having a plurality of 60 openings 13 formed in the top and around the upper portions of the side walls. The member 12 is frusto-pyramidal in form and is provided with a flange 14 resting upon the top of the base, said member forming 65 a heating chamber immediately over the openings 3 in the top of the base.

An outer shell 16 has its lower edge arranged to telescope onto the lower wall portions of the body portion 2 of the base. 70 The shell 16 is frusto-pyramidal in form and is closed across the top by a top plate 17. A vent member 18 is secured upon the back wall of the shell near the bottom thereof and communicates with the shell through 75 an opening 18' registering with the vent.

A baffle plate 21 is mounted within the back of the shell 16, the lower edge of the plate being engaged between the lower edge 80 of the shell and the adjacent surface of the body portion 2 of the base. The plate 21 is offset inwardly from the back wall of the shell 16 at a point immediately below the vent 18 and extends upwardly to a point slightly below the top of the shell in spaced 85 parallel relation to the back wall of said shell, thereby forming a vent passage across the back of the shell to communicate between the top of the shell and the vent 18. The plate 21 is shaped to fit closely between 90 the side walls of the shell.

A top baffle plate 22 is secured upon the upper end of the back baffle 21. The top baffle extends entirely across the upper portion of the shell slightly below the top thereof and substantially parallel to the top plate 17, thereby forming a vent passage across the top of the shell. Vent openings 23 and 24 are formed in the front and rear edges of the plate 22 to communicate between the 100 top vent passage and the main body of the shell and the back vent passage respectively. An intermediate baffle plate 26 is secured along its rearward edge upon the back baffle plate 21. The plate 26 extends entirely 105 across the shell between the baffle 21 and the front and side walls of the shell, said plate 26 being positioned substantially midway between the top of the member 12 and the top baffle plate 22. Vent openings 27 are 110

formed in the front and side edges of the plate 26 to communicate between the upper and lower portions of the shell 16, said openings being formed preferably by striking out portions of the plate upon the edges and doubling the struck out portions back to form flanges 28 along the inner edges of the vent openings.

In operation, fuel issuing from the burner 7, is burned within the base 1, the heat and flame passing upwardly through the openings 3 and into the member 12. The base 1 and member 12 are preferably made of cast iron so as to absorb and hold a high amount of heat. The member 12 is quickly heated to a red heat and the fuel entering said member is entirely consumed before issuing from the member 12 through the openings 13. The products of combustion and a surplus of air circulated upwardly therewith issue from the openings 13 in a highly heated condition and pass upwardly into the body of the shell 16. From the lower portion of the shell, the heated gases pass through the openings 27 into the upper portion of the shell, the circulation being retarded by the restricted passage afforded by the openings 27 so that the front and side walls of the shell will absorb and radiate much of the heat from the gases. The gases pass from the upper portion of the chamber into the upper vent through the opening 23, the circulation being further retarded and the upper walls of the shell absorbing and radiating the heat from said gases. From the upper vent passage, the gases pass downwardly between the back baffle 21 and the back of the shell and pass outwardly through the vent 18.

The baffle plates 22 and 26 shield the top of the shell from direct exposure to the heat from the burner and the member 12, and at the same time retard the circulation of the highly heated gases to such an extent that an efficient radiation of heat from the walls of the shell occurs. The back baffle 21 shields the back wall of the shell from direct heat and thus permits the heater to be placed relatively close to a wall or other object without danger of overheating. The retarded circulation and the relatively long circuituous course followed by the gases around the baffle plates results in a high heating efficiency. After the base 1 and member 12 have been initially heated, the burner may be turned down to consume only a very small amount of fuel and still maintain the member 12 in a highly heated condition. Thereafter the circulation of burned gas and air past the heated member 12 causes the mixture to be highly heated as it passes upwardly through the shell and the shell walls are thus kept heated both by radiation from the member 12 and the upper portion of the

base 1, and by absorption from the passing gases, thus maintaining an efficient heating with a minimum consumption of fuel.

The hipped construction of the upper base portion 2 causes the edges of the shell to engage the base 1 only at the extreme lower edge where the base is heated only to a slight degree. This protects the shell from injury by excessive heating and insures that the heat from the burners will be distributed over the full radiating area of the shell.

While I have illustrated and described the preferred construction, my device may be modified in several details without departing from the spirit of my invention. I therefore do not wish to restrict myself to the exact details disclosed, but desire to avail myself of all modifications which may fall within the scope of the appended claims.

Having thus described my invention what I claim as new and desire to secure by Letters Patent is—

1. A heater comprising a base arranged to be supported over a fuel burner, said base having openings in the top thereof; a heat diffusing member mounted upon the top of the base and covering the openings therein, said member having openings in the upper portion thereof; an outer shell fitted over the base and enclosing the heat diffusing member; a vent formed in the back of the shell; and a baffle mounted within the shell in spaced relation to the back of the shell to form a vent passage from the top of the shell to the vent.

2. A heater comprising a base arranged to be supported over a fuel burner, said base having openings in the top thereof; a heat diffusing member mounted upon the top of the base and covering the openings therein, said member having openings in the upper portion thereof; an outer shell fitted over the base and enclosing the heat diffusing member; a vent formed in the back of the shell; a baffle mounted within the shell in spaced relation to the back of the shell to form a vent passage from the top of the shell to the vent; and apertured plates carried by the baffle and extending between said baffle and the front and side walls of the shell.

3. A heater comprising a base arranged to be supported over a fuel burner, said base having openings in the top thereof; a heat diffusing member mounted upon the top of the base and covering the openings therein, said member having openings in the upper portion thereof; an outer shell fitted over the base and enclosing the heat diffusing member; a vent formed in the back of the shell; a baffle mounted within the shell in spaced relation to the back of the shell to form a vent passage from the top of the shell to the vent; and a plate secured upon the upper end of the baffle plate and ex-

tending across the upper portion of the shell between said baffle plate and the front and side walls of the shell and having a vent opening.

5 4. A heater comprising a base arranged to be supported over a fuel burner, said base having openings in the top thereof; a heat diffusing member mounted upon the top of the base and covering the openings 10 therein, said member having openings in the upper portion thereof; an outer shell fitted over the base and enclosing the heat diffusing member; a vent formed in the back of the shell; a baffle mounted within the 15 shell in spaced relation to the back of the shell to form a vent passage from the top of the shell to the vent; and a pair of spaced parallel plates mounted upon the baffle plate and extending across the upper portions of 20 the shell between said baffle plate and the front and side walls of the shell, said plates having vent openings.

5. A heater comprising a base arranged to be supported over a fuel burner and provided with a tapered upper body portion having a plurality of openings in the top thereof; a heat diffusing member mounted upon the top of the base and having a plurality of openings in the top and upper side 25 portions thereof, said member forming a heat chamber directly over the openings in the base member; a shell closed at the top and having its lower edge telescoping over the tapered body portion of the base; a vent 30 formed in the back of the shell near the bottom thereof; and a baffle plate having its lower edge engaged between the shell and the base and offset to extend upwardly in spaced relation to the back wall of the shell 35 to a point slightly spaced from the top of the shell to form a vent passage across the back of said shell.

6. A heater comprising a base arranged to be supported over a fuel burner and provided 45 with a tapered upper body portion having a plurality of openings in the top thereof; a heat diffusing member mounted upon the top of the base and having a plurality of openings in the top and upper side portions 50 thereof, said member forming a heat chamber directly over the openings in the base member; a shell closed at the top and having its lower edge telescoping over the tapered body portion of the base; a vent 55 formed in the back of the shell near the bottom thereof; a baffle plate having its lower edge engaged between the shell and the base and offset to extend upwardly in spaced relation to the back wall of the shell to a point 60 slightly spaced from the top of the shell to form a vent passage across the back of said shell; and a plate extending from the upper edge of the baffle plate to the front of the shell to form a vent passage across the

top of the shell, and communicating with 65 the back vent passage, said plate having a vent opening formed adjacent the front wall of the shell.

7. A heater comprising a base arranged to be supported over a fuel burner and provided with a tapered upper body portion having a plurality of openings in the top thereof; a heat diffusing member mounted upon the top of the base and having a plurality of openings in the top and upper side 70 portions thereof, said member forming a heat chamber directly over the openings in the base member; a shell closed at the top and having its lower edge telescoping over the tapered body portion of the base; a vent 75 formed in the back of the shell near the bottom thereof; a baffle plate having its lower edge engaged between the shell and the base and offset to extend upwardly in spaced relation to the back wall of the shell to a point 80 slightly spaced from the top of the shell to form a vent passage across the back of said shell; and a plate mounted upon the top of the baffle plate and extending across the upper portion of the shell in spaced relation 85 to the top of the shell, said plate having vent openings formed adjacent the front and back walls of the shell.

8. A heater comprising a base arranged to be supported over a fuel burner and provided with a tapered upper body portion having a plurality of openings in the top thereof; a heat diffusing member mounted upon the top of the base and having a plurality of openings in the top and upper side 90 portions thereof, said member forming a heat chamber directly over the openings in the base member; a shell closed at the top and having its lower edge telescoping over the tapered body portion of the base; a vent 95 formed in the back of the shell near the bottom thereof; a baffle plate having its lower edge engaged between the shell and the base and offset to extend upwardly in spaced relation to the back wall of the shell to a point 100 slightly spaced from the top of the shell to form a vent passage across the back of said shell; a top baffle plate mounted upon the upper end of the baffle plate and extending across the upper portion of the shell in spaced relation to the top of the shell, said plate having vent openings 105 formed adjacent the front and back walls of the shell; and an intermediate baffle plate mounted upon the back baffle plate and extending between said back baffle plate and the side and front walls of the shell, said intermediate baffle plate having openings 110 formed adjacent the sides and front of the shell.

In witness whereof, I hereunto set my signature.

EDWARD NAUER.
